FREDERIC BILLON AND JAKOB BOHLI, OF SOLOTHURN, SWITZERLAND, ASSIGNEES TO SCINTILLA AKTIENGESELLSCHAFT, OF SOLOTHURN, SWITZERLAND.

IGNITION MACHINE.

Application filed August 16, 1926, Serial No. 129,628, and in Germany July 23, 1925.

This invention relates to ignition machines and has for its object to simplify the construction of the stationary part of such machines having a flywheel magnet.

5 The machines of this kind as made at the present time consist as a rule of one or more laminated iron yokes, on which coils are mounted. Machines with such U-shaped yokes and three coils are known, also machines 10 with two separate I-shaped yokes each with a single coil. The former shape is complicated, the three coils which are arranged in a U-shaped manner being in each other's way. In the second case the magnetic circuit is periodically interrupted, which has 15 a detrimental effect on the magnet. Furthermore, these apparatus have laminations which are riveted or screwed together in several places, so that they are complicated 20 and expensive to manufacture.

In the known apparatus the pole pieces and coil cores are as a rule different and separate from one another, so that two different parts have to be made and mounted. In 25 some other types of apparatus the stators are made in one piece, which makes it difficult to place the coil on the core.

The object of the present invention is to 30 simplify and cheapen the manufacture as compared with the known arrangements. This is effected by a three-pole V-shaped stator bearing two coils being so constructed that a single kind of stamping can be used both for the pole pieces and for the coil 35 cores. The pole piece sheets are punched out in one piece with the core part and have a recess at one side, into which the core part of the other pole fits, so that the whole stator consists of single sheets which are 40 inserted in one another. By this arrangement a particularly satisfactory magnetic circuit is obtained.

All the laminations of one pole may be connected together with screws, one screw being 45 used for each pole, so that the expensive method of riveting is done away with. The poles or the stator constructed according to the present invention are fixed to the casing preferably also with a single screw.

50 Obviously the pole pieces formed at the ends of the built up yoke will be such that the sheets are separated from one another by the thickness of a sheet. These spaces may be filled with magnetic material, for instance 55 with a pole piece lamination without a core

piece, or with non-magnetic material. This in itself constitutes a considerable simplification in the manufacture, as the same shape of stamping may be used without the core part.

60 In the accompanying drawing a constructional example of the present invention is shown in perspective view.

Figure 1 shows a single stamping.

Figure 2 shows two layers of stampings 65 adapted to be superposed one on the other are shown, while Figure 3 shows three such superposed layers and two pole piece laminations without the core part.

70 Referring to the drawing in detail, each stamping 5 is provided with a core part 7 and a recess 6 into which the core part 7 of the adjacent stamping fits. The stampings are superposed one upon the other as shown in Fig. 3 and may be secured in assembled 75 relation by screws 8 passing through the apertures 9. In Fig. 3, a screw 8 suitable for the purpose is shown in line above one of the apertures 9 for insertion therein.

75 In Fig. 3, two pole pieces 5^a are shown 80 without the core part 6.

What we claim is:

1. For use with an ignition machine having a rotor in the form of a fly-wheel magnet a stator having three poles, two cores connecting one of the poles with the other two poles and lying at an angle of approximately 60° with respect to one another, each of the 85 said cores being adapted to support a coil.

2. For use with an ignition machine having a rotor in the form of a fly-wheel magnet a stator having three poles, two cores connecting one of the poles with the other two poles and lying at an angle of approximately 60° with respect to one another, each of the 90 said cores being adapted to support a coil, the said poles and cores being constituted by superposed layers of stampings, each 95 layer comprising three stampings, as set forth.

3. A stator as claimed in claim 2 and in which two of the stampings in each layer comprises a pole portion and a core portion of the stator, as set forth.

4. A stator as claimed in claim 2 and in which two of the stampings in each layer comprise a pole portion and a core portion of the stator, and in which adjacent superposed layers are reversed with respect to one another, as set forth.

- 2
5. A stator as claimed in claim 2, and of the stator, and half the stampings con-
having screws for holding the superposed stituting the said other two poles having no
layers of stampings together, one screw be- core part, as set forth. 10
ing provided for each pole, as set forth.
- 5 6. A stator as claimed in claim 2, and In testimony whereof we have signed our
in which two of the stampings in each layer names to this specification.
- FREDERIC BILLON.
JAKOB BOHLI.
